Primary Examiner — Rhea Shields

CLAIM

The ornamental design for an oral care implement, as shown and described.

DESCRIPTION

FIG. 1 is a perspective view of the oral care implement, showing the new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

All broken lines shown in the drawings are for environmental purposes only and form no part of the claimed design. All oblique lines shown in the drawings are used to show transparent surfaces.

1 Claim, 4 Drawing Sheets
